CLAIM

The ornamental design for a portable microphone isolation shield with pop filter, as shown and described.

DESCRIPTION

FIG. 1 is a front perspective view of a portable microphone isolation shield with pop filter, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the portable microphone isolation shield with pop filter, which form no part of the claimed design.

The broken lines depict portions of the portable microphone isolation shield with pop filter that forms no part of the claimed design.

1 Claim, 7 Drawing Sheets
